UNITED STATES PATENT OFFICE.

ALFRED HALL, OF PERTH AMBOY, NEW JERSEY.

TERRA-COTTA KILN.

SPECIFICATION forming part of Letters Patent No. 230,479, dated July 27, 1880.

Application filed June 15, 1880. (No model.)

To all whom it may concern:

Be it known that I, ALFRED HALL, of Perth Amboy, in the county of Middlesex and State of New Jersey, have invented new and useful 5 Improvements in Terra-Cotta Kilns, of which the following is a specification.

Figure 1 is a front elevation of the improvement, shown as applied to a kiln. Fig. 2 is a 10 sectional plan view of the forward part of the kiln. Fig. 3 is a sectional elevation of the door.

Similar letters of reference indicate corresponding parts.

The object of this invention is to construct 15 the doors of kilns for burning terra-cotta in such a way that the heat will be distributed equally through the door and the other parts of the kiln so that all parts of the kiln will have a uniform temperature, and all the articles will 20 be burned evenly.

The invention consists in constructing a 25 door for terra-cotta kilns with flues in its inner part communicating with and forming continuations of the ordinary flues in the kiln-wall, and connected with the furnaces by flues, whereby a uniform distribution of heat all around the kiln will be effected, and all the articles in the kiln will be burned evenly, as will be hereinafter fully described.

30 A represents the furnace-doors, B the ash-pits, and C the door of the kiln D. To the side parts of the door-frame are attached plates E, which project at the sides of the door, and have eyes formed in their outer ends to receive pins F. The pins F also pass through 35 holes in the ends of the U bars or clevises G, between which ends the eyes of the plates E are placed. The bends of the bars G pass through eyes formed upon the ends of the 40 bands H, passed around the kiln D to strengthen it.

Upon the inner ends of the plates E are formed eyes to receive the pins K, which pins

also pass through eyes in the forked ends of the right and left screws L. The screws L 45 pass through right and left screw-holes in the ends of the bars M, which cross the door C, and have a longitudinal slot formed through them to receive a lever, so that they can be turned to draw the screws L inward and firmly 50 clamp the door C in place. With this construction the door C can be removed by removing the pins K, the screws L, and the bars M.

In the inner part of the door C are formed 55 flues I, which, when the door is closed, communicate with and form continuations of the ordinary flues J in the inner parts of the kiln-walls. With this construction the inner part 60 of the door and the inner wall of the kiln will be heated uniformly, so that there will be no cool part of the kiln, and all the terra-cotta articles will be burned evenly.

The products of combustion from the furnaces A are introduced into the flues I of the 65 door C through flues a in the same manner as they are introduced into the flues J in the inner wall of the kiln, so that the heat will be distributed evenly all around the kiln.

Having thus fully described my invention, 70 I claim as new and desire to secure by Letters Patent—

A door for terra-cotta kilns, constructed substantially as herein shown and described, made with flues I in its inner part, communicating with and forming continuations of the ordinary flues J in the kiln-wall, and connected 75 with the furnaces by the flues a, whereby a uniform distribution of heat all around the kiln will be effected, and the articles will be 80 burned evenly, as set forth.

ALFRED HALL.
